UNITED STATES PATENT OFFICE.

EMILIO ALBERTI, OF NEW YORK, N. Y., ASSIGNOR TO INTERNATIONAL CORK COMPANY,
OF BROOKLYN, NEW YORK, A CORPORATION OF NEW YORK.

EJECTING MECHANISM FOR CORK-BLOCKING MACHINES.

Specification of Letters Patent.

Patented Jan. 21, 1919.

1,291,703.

Application filed October 27, 1917. Serial No. 198,842.

To all whom it may concern:

Be it known that I, EMILIO ALBERTI, a citizen of the United States, and a resident of the city of New York, in the county of 5 Kings and State of New York, have invented certain new and useful Improvements in Ejecting Mechanisms for Cork-Blocking Machines, of which the following is a specification.

10 The present invention relates to cork blocking machines, and more particularly to those elements thereof which are used for removing the finished products from the cutters, or in other words to the ejecting devices thereof.

In one type of these machines an ejector in the form of a rod is provided, said rod extending through the rotary arbor and cutter of the machine and being held in position 20 by a bracket on the main frame. The rod is held stationary within the arbor and cutter. The cutter, in completing its stroke toward the work, blocks out a cork from the cork strip, the said cork remaining within 25 the cutter, to be removed therefrom by the ejector, when the cutter moves in the opposite direction. An ejector of this type has several defects, one of the same being the following: The diameter of the rod must 30 be considerably smaller than the inner diameter of the cutter, as otherwise it could not extend through the arbor, and for this reason it will not eject from the cutter chips or broken cork pieces entering the same. These 35 chips or cork pieces seriously interfere with the cutting operation. Another defect of the ejectors heretofore in use consists in that the ejector vibrates or swings within the arbor and cutter inasmuch as the same is supported 40 at one of its ends only. Due to this vibration or swinging motion, the blocker becomes very noisy.

The main object of the present invention is to provide an ejecting mechanism which 45 effectively obviates the defects above mentioned.

With these and other objects in view, which will more fully appear as the nature of the invention is better understood, the 50 same consists in the combination, arrangement, and construction of parts hereinafter described, pointed out in the appended

claims and illustrated in the accompanying drawings, it being understood that many changes may be made in the size and proportion of the several parts and details of construction within the scope of the appended claims without departing from the spirit or sacrificing any of the advantages of the invention.

One of the many possible embodiments of the invention is illustrated in the accompanying drawings in which:

Figure 1 is a central vertical section taken through a portion of a cork blocking machine provided with an ejecting mechanism constructed in accordance with the present invention; Fig. 2 is a top plan view thereof; Fig. 3 is a central horizontal section taken through the cutting mechanism and the ejector therein; Fig. 4 is a similar section showing the elements in other positions; and Fig. 5 is a perspective view of a portion of the ejecting device.

In the drawings only so much of the cutting mechanism has been shown as is necessary to understand the function and operation of the ejecting device. Attention is called to the fact that, while herein the ejecting mechanism has been shown mounted 75 on a blocking machine of a particular type, (the one described in application for Letters Patents, Serial No. 157,489, filed on the 26th day of March, 1917, by myself, Michael Cariti and Gaetano La Femina), it may be 80 used in connection with others just as well.

Referring now to the drawings, the numeral 10 designates a portion of the main or supporting frame of the machine. Upon the table portion of the frame rests a base 90 11, from which rise bearings 12, in which is rotatably and reciprocably mounted a tubular arbor 13. This arbor is provided in its front end with an interiorly screw-threaded portion 14, into which fits the screw-threaded end of a tubular cork cutter or knife 15. For rotating the arbor and cutter, there is held between two of the bearings 12 a pulley 16, provided with a key 17 that is seated in a longitudinal slot 18 in the arbor. Rotation 95 may be imparted to the pulley in any suitable manner. To properly perform the cutting operation, the cutter is not only rotated but also reciprocated. The cutter re-

ciprocating means includes a lever 19, provided with a fork-shaped upper end 20, in engagement with pins 21 upon a ring 22, the latter being loosely mounted upon the 5 arbor between two stops 23. The lever is oscillated from the main driving shaft of the machine (not shown).

The work holder 24 of the machine is disposed upon the table portion of the main 10 frame, and may be of any suitable construction.

The ejecting mechanism comprises three 15 elements, towit: a piston 25 within the cutter, a rod 26 within the arbor, and a stop 27 that is attached to some stationary part of the machine. The piston 25 fits snugly the bore of the cutter and is slidably disposed within the cutter 15 and has attached thereto or made integral therewith a rearwardly extending stem 28, that projects through a hole 29 in the rear head 30 of the cutter into the tubular arbor 13. The stem 28 is screw threaded, as clearly shown at 31, and with these threads mesh those of two 20 nuts 32 and 33, said nuts being disposed within the bore of the arbor. The nut 32 serves, as will hereinafter appear, as a stop, and the nut 33 as a locking means. Upon the free end of the stem 28 is mounted a 25 nut 34, held in position by a cotter pin 35. This nut serves as an abutment. The rod 26 is loosely mounted within the tubular arbor, and is adapted to bear against an enlargement 36 of a bar 37. This bar and 30 its enlargement constitute the stop 27 above referred to. The enlargement 36 is disposed within the tubular arbor, the axis of the same and also of that of the bar 37 coinciding with that of the arbor 13. The bar 35 37 is adjustably secured to a bracket 38, which, in turn is adjustably held upon supports 39, secured to the rear bearing 12. The bracket 38 is provided with a longitudinal slot 40, merging into registering 45 notches 41, through which extends the bar 37. Clamping screws 42 serve to hold the bar 37 in position upon the bracket. The bracket is slidably disposed upon the supports 39, which are made in the form of rods having screw threads 43. Nuts 44, bearing against two faces of the bracket, 50 serve to hold the same in proper position upon the supports 39.

The operation of the device is as follows:—Each cutter of the set with which the machine is furnished is provided with its piston 25 and the parts carried thereby. Before placing a cutter in position upon the arbor 13, the stop nut 32 and the lock 55 nut 33 on the stem 28 of the ejector are shifted on the stem so that the stop nut 32 abuts against the rear face of the head 30 of the cutter, when the front face of the piston 25 is substantially flush with the cutting edge of the said cutter. After the cut-

ter and the ejecting mechanism now described has been put upon the arbor, the said arbor and elements moving therewith are shifted to the end of the idle or return stroke (Fig. 4). The clamping screws 42 70 are then loosened, and the bar 37 brought into engagement with the rod 26 and shifted until the said rod is in a position in which the piston 25 is about flush with the cutting edge of the cutter. The clamping screws 75 are then screwed down, to hold the bar 37 in this position. The device is then ready for operation.

On the working stroke, both the arbor 13 and the cutter 15 thereon move toward the 80 work support. The cutter, in completing its forward stroke, blocks out a cork from the strip 45 (Fig. 3), the said cork causing the piston 25 and the parts attached thereto to move rearward that is to say toward the 85 bar 37. The cork remains within the cutter and is removed therefrom by the ejecting mechanism, when the cutter moves in the opposite direction. As the cutter moves in the direction mentioned, the nut 34 on 90 the stem 28 first comes into contact with the rod 26, causing the latter also to move rearward until it is stopped in its movement by the enlargement 36 of the bar 37. As soon as the rod 26 is stopped, it arrests the 95 motion of the piston 25, which, as the cutter completes its idle stroke, ejects the cork from the cutter. The finished product falls into a chute, to slide into a receptacle below the same, (the chute and receptacle are 100 not shown).

Inasmuch as the piston fits snugly the bar of the tubular cutter, broken cork pieces or chips are conveniently ejected from the cutter, and thus cannot interfere with the 105 proper operation of the machine. The bar 37 is too short to oscillate or swing, so that unnecessary noises are avoided in operation.

What I claim is:

1. A tubular cork cutter having a cutting 110 edge at one of its ends and a head upon its other end provided with a hole, a piston snugly fitting the bore of said cutter slidably mounted therein and having a rearwardly projecting stem extending through 115 said hole, an abutment upon the outer end of said stem, and a stop upon said stem intermediate said abutment and the outer face of the head of said cutter.

2. A tubular cork cutter having a cutting 120 edge at one of its ends and a head upon its other end provided with a hole, a piston snugly fitting the bore of said cutter slidably mounted therein and having a rearwardly projecting stem extending through 125 said hole, an abutment upon the outer end of said stem, and a stop adjustably mounted upon said stem intermediate said abutment and the outer face of the head of said cutter.

3. A tubular cork cutter having a cutting 130

edge at one of its ends and a head upon its other end provided with a hole, a piston snugly fitting the bore of said cutter and slidably mounted therein and having 5 a rearwardly projecting screw threaded stem extending through said hole, an abutment upon the outer end of said stem, and a nut

in mesh with the threads of said stem intermediate said abutment and the outer face of the head of said cutter. ¹⁰

Signed at New York, in the county of Kings, and State of New York, this 22nd day of October, A. D. 1917.

EMILIO ALBERTI.
